UNITED STATES PATENT OFFICE.

ROBERT O. FERGUSON, OF BRISTOL, TENNESSEE, ASSIGNOR OF ONE-HALF TO LOUIS G. STERCHI, OF BRISTOL, TENNESSEE.

ANTIGLARE SCREEN FOR HEADLIGHTS.

Application filed March 28, 1927. Serial No. 179,058.

This invention has relation to headlights for automobiles, locomotives, or other purposes, and is particularly concerned with devices for preventing the objectionable glare thrown out by such lights.

It has been proposed heretofore to provide various arrangements of screens which are placed either in front of, or in some relation to the light or its reflector in order that the beam of light will be obscured in whole or in part so as to prevent the objectionable glare, which frequently causes accidents because of its blinding effect upon the driver of an approaching vehicle. The present invention is concerned with screens of this character, but embodies certain improvements therein which produce superior results, in that the objectionable rays are obscured so that they are prevented from injuriously affecting the sight of an approaching motorist, and at the same time the beam of light is projected upon the roadway in a manner to illuminate the same even better than if the device was not used.

With the above, and other important objects in view, the invention consists in the construction hereinafter more particularly described, the novel features of which will be pointed out in the following claims.

In the accompanying drawings, which illustrate preferred embodiments of the invention:

Fig. 1 is a vertical sectional view of a screen, the lamp to which it is applied being shown by broken lines;

Fig. 2 shows the same form of screen in front elevation;

Fig. 3 is a front view of a lamp with a slightly modified form of screen applied thereto;

Fig. 4 is a front elevation of the screen illustrated in Fig. 3 apart from the lamp, and

Fig. 5 is a vertical sectional view on the line 5—5, Fig. 4.

Referring first to Fig. 2, the screen 1 is in the form of a sector or wedge, and comprises the inclined, converging sides 2, arcuate top portion 4, and slats 6 which are supported from the inclined sides 2 by reduced neck portions 8, the slats being angularly turned in parallelism so as to incline downwardly and outwardly from the inside of the lamp. Below the parallel arc-shaped slats 6 is a circular slat 10, also connected

with the sides of the screen by reduced portions, 10^a, whereby it may be tilted in parallelism with the slats 6, that is, downwardly and forwardly from the inside portion of the lamp.

Tabs or attaching members 12 extend from the arcuate rim 4 upwardly, and a single tab 14 extends downwardly as an extension from the inclined sides 2. The tabs 12 and 14 are bendable, and may, as shown in Fig. 1 be bent over a rim portion of the lamp to anchor the screen or anti-glare device in position. Preferably, but not necessarily, the screen is positioned back of the lens L of the lamp and in front of the light 15, although it may be located in front of the lens, but this is not as convenient a method of assembly as where the screen is positioned back of the lens and inside of the lamp where it will be protected from disarrangement.

When located in the position shown it will be seen that the screen as an entirety is sector-shaped, being formed as a narrow wedge, and that the slats are turned angularly about their centers or axes 8. This arrangement results in cutting out or screening the direct parallel rays from a sector-shaped portion of the beam of light projected from the reflector R, and this section obscures a portion of the rays which would be projected forwardly, and such rays are those that would produce the objectionable glare. The rays of light which are reflected against the back of the slats 6 of the screen are in part returned to the reflector R and in part reflected downwardly upon the road in front of the light, the lowermost slat 10 being positioned directly in front of the light 15, the direct rays of which latter are accordingly screened and are prevented from being projected forwardly in a line parallel with the axis, such rays being partly reflected upwardly and backwardly, and partly downwardly and forwardly, as is the case with the rays of light projected against the inside of the slats 6.

The screening effect of this device has upon actual demonstrations thereof been shown to be successful, and to, moreover, effectively illuminate the roadway in front of the automobile. By curving the slats 6 upon arcs which are concentric with the curvature of the lamp reflector the casting of shadows upon the road is avoided and the

rays projected by the lamp are so directed that no upgoing rays are permitted, the latter being the rays which ordinarily interfere with the vision of approaching motorists.

5 The peculiar shape of the device cuts out these rays, and completely eliminates the objectionable glare.

In the modified construction shown in Figs. 3, 4 and 5, two wedge-shaped screens 10 are combined to produce a construction in which the upper rays as well as the lower rays are obscured, while sufficient of the beam remains unscreened to successfully illuminate the road in front of the vehicle.

15 This construction includes an upper curved rim 41 from which extend downwardly converging side portions 43, and a lower curved rim portion 42 having upwardly extending convergent sides 44. Arc shaped slats 16 20 are suspended by narrow portions 16^a between the convergent sides of the upper and lower portions of the screen, the slats 16 being all inclined downwardly, as shown in

Fig. 5, and being bent from the axes 16 25 of the slats, so that said slats extend equally upon opposite sides of the plane of the screen as an entirety, as shown in Fig. 5. At the

30 central portion of the screen a preferably circular slat 18 is supported from its axial portions 18^a, the slat being adapted for location immediately in front of the lamp, the same as the slat 10, shown in Figs. 1 and 2. Upper and lower tabs 13 project from the curved extremities 41, 42, respectively,

35 of the screen, and are adapted to be bent about the circular portion of the lamp for attaching the screen in position thereon, as in the construction first described. In this form of the device it will be noted that those 40 rays of the beam of light which would be projected below the center of the light, and would constitute an objectionable glare, where the light was placed higher than the elevation of the headlights in an ordinary

45 automobile, would be obscured. This form of the device is accordingly particularly useful in connection with locomotive headlights, or other headlights which are placed high, and where a screening device like that 50 shown in Fig. 2 would not be effective to obscure the lower rays, and prevent said rays from dazzling the sight of a person immediately in front of the light.

In both of the constructions illustrated, 55 it is to be observed that an important feature of the invention consists in constructing the screen of a wedge shape, as a sector having a relatively short arc, and at the same time providing slats which are curved on the 60 arcs of circles concentric with the curvature of the reflector of the lamp. The proper

amount of the beam is accordingly by such construction prevented from being projected along lines parallel with the axis of the lamp, and at the same time the rays of 65 light which are thus obscured are reflected downwardly upon the road in front of the lamp, and in such manner that such rays and those which are not cut out by the screen are combined to effectually illuminate the 70 roadway in front of the motor vehicle to which the lamp is attached. The invention is accordingly useful in its perfect elimination of the glare of a headlight, and may be used with any kind of glass or other lens 75 with perfect safety. When used, it will be found that the device results in so deflecting and diffusing the light as to improve the illumination of the roadway as compared with the case where the ordinary lens 80 is employed, it being well known that the lenses which are approved as being theoretically anti-glare, are in fact more or less objectionable on this ground.

Any suitable or appropriate material may 85 be used for the screen, such for example as sheet metal, celluloid, glass, or the like.

I claim:

1. As an article of manufacture, a screen 90 for headlights comprising a wedge-shaped frame of thin sheet opaque material, having sharply converging sides and an arcuate top, the sides extending beyond the top to form attaching tabs and a leg extending from the point of convergance of said sides to form 95 a third supporting member, a plurality of concentrically curved, parallel spaced slats, extending between said sides, and a light obscuring disc located in front of the source of light so as to obscure the direct rays 100 therefrom, and entirely cover the light, the center of said disc being concentric with the curvature of said slats, said slats and disc being inclined from their upper edges downwardly and forwardly.

2. As an article of manufacture a screen 105 for headlights, comprising a wedge-shaped frame of sheet opaque material having sharply converging sides and an arcuate top, a plurality of concentrically curved parallel 110 slats extending between said sides, and a light obscuring disc adapted to be located directly in front of the source of light so as to obscure the direct rays therefrom, the center of said disc being concentric with the 115 curvature of said slats, and means whereby said screen may be supported in proximity to the lens of the headlight.

In testimony whereof I have hereunto set my hand this 28 day of March, A. D. 1927.

ROBERT O. FERGUSON.
